COAL BREAKING MECHANISM

Robert M. Barr, Fort Smith, Ark.

Application October 2, 1941, Serial No. 413,375

3 Claims. (Cl. 83—52)

This invention relates generally to improvements in colliery machinery and pertain particularly to a machine for reducing the size of lumps of coal to a desired proportion.

Coal as brought from the mine is in large part made up of very large lumps which are sometimes as much as thirty inches wide. This coal goes through a shaker where the lumps are reduced to sizes of desired proportions. It has up until the present time been the practice at various mines to employ men to reduce the sizes of the lumps in the shaker by the use of picks and this results in the formation of a large quantity of fine coal or slack which the mine operators desire to avoid since there is already a larger quantity than is desired in the coal as mined.

The present invention comprises a machine which operates over the shaker to break down the lumps of coal on the shaker to a desired size with the formation of a minimum amount of slack.

Another object of the invention is to provide a machine for reducing the lumps of coal on the screens to a desired size by the employment of picks or chisels which are pressed against the lumps of coal to break the same without producing an excessive amount of chips or small particles.

The invention will be best understood from a consideration of the following detailed description taken in connection with the accompanying drawings, it being understood, however, that the invention is not to be considered as limited by the specific illustration or description but that such illustration and description constitutes a preferred embodiment of the invention.

In the drawings:

Fig. 1 is a sectional view taken transversely on line 1—1 of Fig. 2 showing in elevation over the screens the breaker machine embodying the present invention.

Fig. 2 is a vertical section taken substantially on the line 2—2 of Fig. 1.

Fig. 3 is a sectional view taken vertically substantially on the line 3—3 of Fig. 1.

Referring now more particularly to the drawings the shaker screen structure is indicated generally by the reference character S, this screen structure being of usual well-known design which includes the side plates or walls 10.

Located in a horizontal plane above the shaker screen and extending longitudinally thereof, substantially directly over the side walls 10 are pairs of beams 11 while disposed between the pairs of beams 11 are longitudinally extending spaced beams 12. These beams function as

supporting means for the breaking machine about to be described.

Each pair of beams 11 supports a pair of spaced bearings 13 which are aligned transversely of the beams and which in turn support a short horizontal shaft 14. Each of the shafts 14 has connected therewith between the bearings 13, a depending shaft 15.

Extending transversely of the breaker screen and through the side walls 10 thereof is a bar 16 to each outer end of which the lower end of a guide shaft 15 is coupled as indicated at 17.

As is shown in Figs. 2 and 3 there are two of the shafts 14 upon each pair of beams 11, the two shafts 14 being spaced apart longitudinally of the beams and consequently there are at each side of the breaking machine two of the depending guide shafts 15 which are attached to the adjacent underlying side walls of the breaker screen.

Extending transversely of the shaker screen are the two horizontal beams 18 each of which supports a plurality of picks or chisels 19. Each beam 18 is located between a pair of the transversely spaced beams 15 and secured to each end of each beams 18 is a guide sleeve 20 through which the adjacent guide beam 15 passes. Thus the pick or chisel beams 18 are supported for vertical reciprocal movement so that the points of the chisels or picks 19 may be moved downwardly to be forced through lumps of coal on the shaker screen.

Directly above each pick or chisel beam 18 is a gear shaft 21 which is supported by the central beams 12 through the medium of bearings 22 and upon the outer end of each shaft 21 is secured a gear 23.

Each of the gears 23 carries upon the outer side thereof an eccentric pin 24 with which is connected one end of a longitudinally adjustable pitman 25. The lower end of each pitman 25 is pivotally connected as indicated at 26 with the underlying pick beam 18.

Extending transversely beneath the beams 11 and 12 and midway between the shaft 21 is a driving shaft 27 which is supported by suitable bearings 28 secured to the undersides of the beams 12 and a bearing 29 secured to the under side of an outer one of one pair of beams 11 as shown in Fig. 1. This driving shaft carries upon its outer end a pulley 30 and it also carries and has secured thereto the pair of pinions 31 each of which is rotated between and has toothed connection with a pair of adjacent gears 23 as shown in Figs. 2 and 3.

As is also shown in these figures the pitman are coupled with the gears 23 in such a manner that when rotary motion is imparted to these gears by the drive shaft 27 and the pinions 31 the pick bars 18 will be given opposite movement, that is, when one bar is moving upwardly the other one will be moving downwardly.

Any suitable means may be employed for driving the shaft 27 but there is here illustrated, in Fig. 3, an electric motor 32 supported in a suitable manner adjacent to the pulley 30 and connected with the pulley 30 through the medium of a belt 33 which passes around a smaller pulley 34 which is coupled with the armature shaft of the motor.

With the machine here described it will be seen that the picks or chisels when moved downwardly against underlying lumps of coal will be pressed through the lumps and consequently will break the same with the formation of less slack than would be the case in the use of hand picks which are driven against the lumps with a force which imparts a pounding or jarring to the lumps and causes the formation of many chips.

From the foregoing it will be readily apparent that the machine herein described will function efficiently to break up large lumps of coal in the shaker screen and reduce the same to a desired size with the formation of a minimum of slack and also it does not require the services of an attendant as is required under the present process.

What is claimed is:

1. A lump material breaker of the character described, comprising means for supporting said material, suspended swinging carrier means for said supporting means, a plurality of pick elements, a carrier body for said pick elements extending transversely of the material supporting means and having sliding connection with said swinging carrier means whereby the said picks

are directed downwardly toward the material carrier, and mechanism connected with said pick carrier for effecting the vertical reciprocation of the same upon said carrier means and with respect to the material supporting means.

2. A lump material breaking machine comprising a supporting structure, a lump material carrier disposed beneath the supporting structure, a hanger shaft oscillatably suspended from the supporting structure and coupled with said material carrier at opposite sides of the same, a bar extending transversely of the material carrier and having sliding connection at its ends with said hanger shafts to facilitate its vertical movement, a plurality of material breaking picks carried by said bar and extending downwardly toward the material carrier, and mechanism supported by the supporting structure and operatively coupled with said bars for effecting the reciprocatory movement of the latter and the picks carried thereby.

3. A lump material breaker of the character stated comprising a supporting structure, a lump material carrier disposed beneath the supporting structure, a pair of hanger shafts at each side of the material carrier each suspended from said supporting structure for oscillation on an axis extending transversely of the material carrier, said hanger shafts being pivotally connected with the material carrier, a bar extending transversely of and above the material carrier between each transversely spaced pair of hanger shafts, a plurality of pick members carried by each bar and directed downwardly toward the material carrier, a vertical tubular guide secured to each end of each bar and having a hanger shaft extending therethrough, and power means operatively coupled with each bar for effecting reciprocal movement of the same relative to the material carrier.
